OR

D20,095

EX

UNITED STATES PATENT OFFICE.

THEOPHILUS REICHARD, OF BROOKLYN, NEW YORK.

DESIGN FOR A TOWER.

SPECIFICATION forming part of Design No. 20,095, dated August 12, 1890.

Application filed March 27, 1890. Serial No. 345,609. Term of patent 7 years.

To all whom it may concern:

Be it known that I, THEOPHILUS REICHARD, a citizen of the United States, residing at Brooklyn, in the county of Kings and State 5 of New York, have invented a new and original Design for Towers, of which the following is a specification, reference being had to the accompanying illustration, forming a part thereof.

10 In the illustration is represented in perspective a tower produced by my new design.

The leading features of my design consist, first, in the peculiar shape or configuration of the tower, and, second, in the ornamentation 15 of the tower by raised surfaces and leaf-like designs, all as will be fully set forth.

Referring to the illustration, let *a* represent the tower, which in general shape is spire-formed, or tapering from the bottom upward 20 to the top thereof.

b is a square base on which the tower is supported, having openings on the sides to represent doors *c c*. Above the base *b* is the tower-base *d*, which is also square in general 25 contour, but is rounded off at the corners, and its upper surface has a curved outline projecting upward to a circular top, on which the standard rests.

a is the standard or tower, being a hollow 30 shaft of uniform annular form, its lower section *f* having the appearance of an interlaced series of lines or open net-work. This section has its lower end ornamented by a bead or raised band *g*, below which the surface is 35 plain, as seen at *h*. At the upper end of the section *f* the tower is projected outward on all sides to form a square platform-like surface *i*, having on its under part a leaf-like orna-

mentation *j*, springing from a beaded band *k*. Above the platform *i* is a base *l*, having 40 a curved outline and tapering to the top, where it is surmounted by a beaded band *m*. From this rises a second section *r*, also of uniform size, which has a similar beaded band and platform projection *u*, with leaf-like ornamentation. Above this is a third section *o*, which tapers to the top and is tipped with a similar platform projection *v*, with like ornamentation, and is surmounted by a ball-shaped top *o*. The lower section *f* 45 is ornamented by a series of vertical raised lines or surfaces *p p*, and over these are placed a continuous line or band that winds around the shaft, as seen at *q*, producing the effect of open-work. The next section *r* has a series 50 of vertical lines *x*, over which are raised lines *s*, which encircle the shaft, giving the effect of square open-work. Below each platform are suspended four cables *c'*, which are connected by triplets to the corners of the base 55 *t*. From points equidistant between the platforms are suspended similar cables in groups, extending from four points on the shaft, (cables *w*,) which spread outward and cross the vertical cables, giving the effect of a net- 60 work of cables that encircle the tower.

Having now described the features of my new design, what I claim, and desire to secure by Letters Patent, is—

The design for a tower, herein shown and 65 described.

THEOPHILUS REICHARD.
